UNITED STATES PATENT OFFICE.

CARL F. SCHULZ, OF BROOKLYN, NEW YORK.

THERMO-ELECTRIC CARBURETER.

1,216,613.

Specification of Letters Patent. Patented Feb. 20, 1917.

Application filed February 24, 1913, Serial No. 750,210. Renewed January 5, 1917. Serial No. 140,844.

To all whom it may concern:

Be it known that I, CARL F. SCHULZ, a citizen of the United States, residing in the borough of Brooklyn, county of Kings, city 5 and State of New York, have invented certain new and useful Improvements in Thermo-Electric Carbureters, of which the following is a specification.

This invention relates to carbureters and 10 has for its object to provide means for electrically heating the fuel for a gas engine, especially during the mixing and gasification of the elements, which elements in some instances will also be separably 15 subjected to the influence of the electric heater.

A carbureter embodying this improvement will be particularly useful in starting by supplementing the carbureter heated by the 20 exhaust gas from the engine. After the engine has commenced running smoothly, after starting, the gas will heat the gas-heated carbureter, and the electrical energy of the batteries need no longer be drawn on for 25 purposes of heating.

My invention also contemplates the construction of a carbureter combining in one device means for heating by electricity and by exhaust gas which may be used 30 jointly or separately as desired.

One practicable embodiment of my invention is illustrated in the drawings accompanying this specification, wherein—

Figure 1 is a central longitudinal sectional view;

Fig. 2 is a cross-sectional view taken on a plane at about the line 2—2, Fig. 1; and

Fig. 3 is a detail of one of the mixing chamber ends.

The mixing chamber in the present showing is made up of a number of cylindrical elements connected together. These elements in the present showing comprise two members 1 and 2 which have screw-threaded connection with each other, and a member 3 45 which has screw-threaded connection with member 2. Member 3 is provided throughout most of its length with a porcelain or other insulation sleeve 4. Within the sleeve 4 and the members 2 and 1 are located the 50 thermo-electric devices which will heat the gas prior to mixing and after and during the mixing.

An end plate 5 is provided for supporting the various parts of the device and holding 55 them together. This plate in the present showing is a flange at the end of the mem-

ber 1. To this flange is secured a plate 6 which will be in connection with the source of electrical supply, as for instance, by means of the conductor 7. The plate is provided with a hub which supports an electric conductor-bar 8. This bar extends in the present showing through members 1 and 2 and into the front end of member 3. Sleeves 9 and 10 are mounted upon the bar 8 and are of substantially the same length. 60 as are the members 1 and 2. Within the mixing chamber are disposed a plurality of conical spiral wires 11, 12. Each of these wires is made of some suitable resisting metal so that upon the passage of the electrical current the wire will become hot. 65 The larger end of the conical spiral is directed toward the inlet and the smaller end toward the direction of flow. The spiral 70 will be of such dimensions that its maximum diameter will be substantially the maximum diameter of the annular space between the walls of the mixing chamber and the sleeve about bar 8, and its minimum diameter 75 will be the minimum diameter of such annular space. In the present showing one convolution (the last convolution at the smaller end) will embrace the rod 8 where this is exposed at the end of the sleeve, and 80 the larger end will lie between the abutting ends of the mixing chamber casing sections. 85 The sections shown are provided at one end with a flange 13 for screw-threaded connection with the coupling 14 of the other member, and a flange 15 of such proportion that 90 a space will be left for receiving a convolution of the wire upon the outer side. The wire will pass through a suitable hole 16 (see Fig. 3) from the inside to the outside 95 and then be given the convolution 17 which will act as a packing between the sections.

The section 3 is shown as of considerably greater length than is the length of the combined sections 1 and 2. Within this section 100 is the porcelain lining 4 above referred to, which lining communicates at the rear with the air inlet 18. Within the sleeve is located the oil nozzle 19 which is connected by a suitable connection 20 with some oil-supplying device. The nozzle extends through the greater part of the chamber 3. The porcelain lining 4 tapers from the rear end to a point adjacent the discharge end of the nozzle 19 so that the air space is 105 gradually carried down toward such nozzle and then the lining flares toward the other

end so that the mixing chamber space will be gradually but quickly enlarged to its full diameter. The heating coil 21 is shown located in the space within the lining 4 and between such lining and the nozzle 19. Such coil in the present instance is connected between a flange at the end of the casing member 3 and the end of the lining 4 where one of its convolutions is enlarged and the front end is wrapped around the nut 22 on the end of the bar 8. The heating coil 21 is a conical spiral, it conforming to the taper of the lining 4.

The plate 6 is held in position on the plate 15 or flange 5 by means of suitable bolts 23 which clamp fiber or porcelain insulators 24 against such plate by means of the discharge nozzle coupling 25. Suitable openings 26 are provided in the plate 6 for the passage 20 of the gas. A connecting pipe 27 is shown for leading the gas from the nozzle 25.

The frame of the device will be the ground connection and the current will be led in, as before stated, at the connector 7 so that the current will pass from the bar 8 25 to the various heating coils 11, 12 and 21 and from these to the casing members and the frame of the machine.

In some installations it may be desirable 30 to use this device as auxiliary to the carbureter which is heated from the exhaust gases, as for instance in starting. It may, however, in some instances be desirable to use this carbureter continuously, or it may 35 again be found that at times with one mixing chamber the electrical device may be employed for starting and after the exhaust gases have arrived at sufficient heat and regularity of discharge to effect the heating, to use the gases for the purpose of 40 heating the same mixing chamber. For this purpose a jacket is shown comprising a casing 28 having an inlet 29 and an outlet 30 for the exhaust gases from the engine, so that there is a chamber space 31 45 provided around the mixing chamber for the purposes above referred to. The casing 28 is held in place by engaging at the front end the flange or plate 5 and at the back end being engaged by a coupling 32 which has screw-threaded connection with the casing 28 and with the mixing chamber member 3, which also carries the air and oil 50 inlets.

55 When it is desired to electrically heat the carbureter oil will be admitted by means of the nozzle, and during its passage through the heating coil 21 it will be heated prior to its introduction to the air. The air 60 will also be heated by passing through and around the coil 21 prior to such introduction. After the air and oil meet the preliminary mixing will be in the flaring portion of the porcelain shell 4 and thence that 65 mixture will pass through a plurality of

heating coils (coils 12 and 11 in the present showing), and be discharged in proper mixed and heated condition for delivery to the engine cylinder or other point of utilization. It may be desirable to preliminarily heat the device prior to starting the engine by permitting the exhaust gases to pass through the chamber 31, or in some instances, as before stated, it may be desirable to interchangeably use the electrical 70 heating means or the exhaust gas heating means afforded by this device.

The electrical heating device is in the form of a screen disposed in the chamber between the inlet and the outlet and presents a plurality of wires between which the air must pass in its passage from the inlet to the outlet.

The screen is disposed along the path of travel of the gas so that the gas flows over 85 the screen as it were as well as passing through it.

Although but one practicable embodiment of the carrying out of the invention has been shown, it will be apparent that changes 90 of construction may be made within the scope of the claims without departing from the spirit of my invention.

I claim as my invention:

1. In a carbureter, the combination with 95 an air inlet, of an oil nozzle disposed therein, and a thermo-electric coil surrounding the said nozzle and extending beyond the discharge end thereof.

2. In a carbureter, the combination with 100 an air inlet, of an oil nozzle disposed therein, and a thermo-electric coil disposed in the air passage space of the said inlet and surrounding the said nozzle and extending beyond the discharge end thereof, for heating the air and the oil prior to their introduction and for further heating the same 105 thereafter.

3. The combination with a substantially cylindrical mixing chamber having at its 110 ends an inlet and an outlet respectively, and a series of conical spiral resistance wires disposed therein.

4. The combination with a substantially cylindrical mixing chamber having at its 115 ends an inlet and an outlet respectively, and a series of conical spiral resistance wires located therein with their smaller ends disposed toward the direction of gas flow.

5. The combination with a substantially 120 cylindrical mixing chamber, annular in cross-section, having at its ends an inlet and outlet respectively, and a series of conical spiral resistance wires located therein with their smaller ends disposed toward the 125 direction of gas flow, each of said spirals having a maximum and a minimum diameter corresponding to the maximum and the minimum diameter of the mixing chamber.

6. In a carbureter the combination with a 130

5 cylindrical air inlet, of an oil nozzle centrally disposed in said inlet, a heating coil disposed in the annular space between the surface of the nozzle and the wall of the inlet and out of contact with each of these, for heating the air and oil preliminarily to their introduction, a substantially cylindrical mixing chamber having at its ends 10 an inlet and an outlet respectively, and a series of conical spiral resistance wires located therein with their smaller ends disposed toward the direction of gas flow.

7. In a carbureter the combination with a 15 substantially cylindrical mixing chamber composed of a plurality of separable sections, of a centrally disposed electrical conductor therein, sleeves thereon corresponding in length to the chamber sections, a

series of conical spiral resistance wires each having its largest convolution clamped between meeting chamber sections and its 20 smallest convolution clamped between meeting sleeves.

8. In a carbureter, the combination with a mixing chamber, of a thermo-electric coil 25 disposed therein, the chamber being provided with an inlet and an outlet, one of these communicating with the chamber outwardly of the coil and the other inwardly thereof whereby the mixture must needs 30 pass through the spaces between the convolutions of the coil.
